UNITED STATES PATENT OFFICE

ENOCH T. FERNBREN, OF TOLEDO, OHIO, AND GEORGE L. MESTLER, OF ROCHESTER,
NEW YORK; SAID FERNBREN ASSIGNOR OF ONE-EIGHTH TO JULIA A. FERNBREN,
OF TOLEDO, OHIO

DISPLAY AND VENDING CABINET

Application filed May 26, 1928. Serial No. 280,809.

This invention relates to that kind of show and display cases or vending machines which are known as service cabinets, being largely used by wholesale business concerns as a means to give retailers, principally grocers, a weekly supply of freshly roasted coffee.

In order that the weekly or semi-weekly service of freshly roasted product, such as coffee may be successfully carried on to the advantage and satisfaction of all parties and to the benefit of the ultimate consumer, it is necessary that a cabinet of this type be not only a good display machine, but it must also be so organized and constructed that it will positively retain the good quality of the coffee or any other likewise sensitive product, while being otherwise time and labor-saving to the retailer, and practical in other aspects.

20 The first object of our invention is to save the consumer the package cost; the average coffee being packed in tin cans, glass jars and fancy paper containers. The reason coffee is thus packed is to preserve the quality, but this method is relatively costly, and this cost is ultimately passed on to the purchaser.

Our next object is to insure to the consumer that the kind and quality of coffee retailed through our sealed-tight cabinet will have full and complete body strength, flavor and aroma.

Another object is to give the retailer a means whereby he may increase his coffee sale due to the following reasons: First, our counter-cabinet acts as a salesman, being in constant view, suggesting the purchase of coffee. Second, the retail merchant can pass on the saving of package cost to the ultimate consumer. Third, the seal-tight arrangement of our cabinet insures excellent quality, which is always fresh, also there is considerable saving of time and labor due to the fact that the approximate quantity of a full half-pound or pound may be obtained by practically one operation. There is also con-

siderable benefit to the retailer in this, that he may purchase freshly roasted coffee daily or weekly, as required, thereby eliminating the requirement of keeping a large supply of roasted coffee on hand in bags, bins or other places which deteriorate the quality. 50

Another object resides in that our cabinet provides the wholesaler or coffee roaster with a means whereby he may safely market his present blends of coffee or any brand at an actual saving in package costs, while the feature of our cabinet insures the qualities of his roasted product, keeping it fresh and free from contamination. 55

While mechanism of the general character here shown are not entirely unknown, it is our belief that the features herein brought out constitute both novel and useful advances in this particular line of devices. 60

To facilitate the objects mentioned, our improved construction brings into coordination a proper gravity feed or flow with means for measuring in half-pound and pound quantities and for automatically arresting and cutting off gravity feed. 65

As granular materials such as tea and coffee, and particularly finely ground coffee, have a tendency to pack, agitating means are provided to insure prompt response to gravity action at time of measuring or drawing off the material into the scoop shown. 75

The construction also provides seal-tight and insulating features, so that no air current may reach the material, to cause deterioration. 80

The main containing space of the base portion has closed off compartments to reduce the air space at the measuring point, which closed off air space also normally acts to keep a more uniform temperature in the central portion of base. 85

As it oftentimes happens that inquisitive persons try to operate the mechanism for measuring the coffee, an automatic locking 90

device is provided which will normally prevent measuring action, as will be herein-after more fully pointed out.

The usefulness of the cut-off mechanism, and the divided scoop which are important features of the invention, as well as the therewith related agitating means and control features of feed, will be now fully explained in the specification and claims.

10 In the drawings:—

Figure 1 shows the dispensing container in elevation;

15 Figure 2 is a top plan view of the bottom cover, showing partitions carried thereby;

Figure 3 is a side view of the same;

16 Figure 4 is an edge view of the same;

Figure 5 is a vertical section of the lower portion of the container;

17 Figure 6 is a perspective view showing one type of scoop;

Figure 7 is a vertical section on line 7 of Fig. 5;

18 Figure 8 is an elevation of the upper portion of the container, partly in section, showing the locking and sealing means for the ring and glass cylinder;

19 Figure 9 is a similar view to Figure 8 showing sealing and locking means of the top to the ring;

20 Figure 10 is a plan view of the base and valve arrangement;

21 Figure 11 is a sectional perspective of the valve lock and means for adjusting the throw of the lever for controlling the valve action, and glass cylinder;

22 Figure 12 is a detail section of a modified form of the oscillating means for agitating materials in the spout.

23 The base portion 13 is provided with a bottom cover or plate 14 which has a downwardly inclined wall terminating at its exterior periphery in an upturned side wall portions 15. Mounted on the plate are partition walls 17, which are shaped to have edges fit snugly against the inner face of the base where the bottom plate is secured fast to the corner lugs at the inner side of the lower rim of the base. See Fig. 7.

24 The purposes of the partition walls 17 are to divide the inner space of the base into two inaccessible closed side chambers and one accessible central compartment which latter by the positioning of the walls 17 is shaped to conform somewhat with the outline of the scoop 18 and thus keep the scoop in proper location relative to the feed mouth 23, see Fig. 7. By this arrangement the closed air spaces 20 will act to insulate the base against sudden temperature changes.

25 The scoop 18 has a handle 21 and a central partition wall 22. The purpose of the wall 22 is to provide two receiving compartments in the scoop directly beneath the delivery mouth 23 of the spout 19.

26 The valve plate 24 is held against the low-

er surface of the mouth or lower opening 23 of said spout by means of the lever 25, see Figs. 5 and 10, which lever is fulcrumed at 26 by means of the pin 27, the slotted portion 28 of the base assembly providing clearing space for a reciprocative movement of the lever 25 when the handle 29 is moved to right or left of its normal position in which said lever is held by means of two springs 30 of which one only is shown in Figure 10. When the lever is moved, the valve plate 24 is thereby moved to expose or open a side portion of the mouth or opening 23 of the spout 19.

27 When this occurs the material held in the spout will drop or flow down into that compartment of the scoop 18 which lies directly therebeneath thus filling the same about as indicated by the dotted lines 31 in Figs. 5 and 7, the flow ceasing when the pile of material in the scoop compartment reaches to the spout. The lever handle is then released which allows the springs 30 to restore the lever to its central position and during this movement the valve plate 24 sweeps across the mouth 23 of the spout 19, closing that portion of this opening which was previously exposed; the downturned edge 32 (Figure 7) of the valve moving the material inwardly to prevent it running over the outer sides of the scoop 18 as the valve cuts off the feed.

28 A further function of the downturned edges on the valve plate 24 is that these edges will tend to reduce the flow of the granular material in the direction of movement of the valve 24, also a slight downcurve of the edges will prevent liability of a grinding friction with the lower edge of the spout.

29 The spiral spring member 33 shown in Fig. 7 which is attached at 34 to the valve plate 24, functions as an agitator in the material above the valve, so that when the valve is moved to the right or left, this spring will break the inter-material empty space usually formed in closely packed granular materials when some of the material is allowed to run out from the bottom of a pile of such material, and force the material to flow freely through the exposed opening of the spout, the dotted spiral lines 35 and 36 indicating right and left positions of the spring 33 caused by the movement of the lever 25.

30 It is essential that the lever 25 be kept locked when the scoop is removed to prevent accidental flow of the material from the spout; also it is desirable that the lever be locked when only partly or carelessly moved in order to prevent the outflow of the material into the scoop when not required.

31 This feature eliminates the liability of deterioration of the material from exposure, and also insures the purchaser of coffee, tea or other materials that the usual quality of this merchandise or guaranteed brands will

be maintained. This locking feature is best shown in Fig. 11, the bracket 37 being secured to the inner side of the base wall 38, carrying a locking pin 39 which is held in engagement with a recess or perforation 40, in the lever 25, by means of the spring 41, which spring bears against the collar 42 of the pin 39, and the lower arm 43 of the bracket, thus causing the upper tapered point 46 of the pin to lock the lever.

When releasing the lever for measuring movement the forked claw 44 which is secured to and projects from the inner wall of the rear end of the scoop, will engage the lower head 45 of the pin, and depress the pin, as the scoop is fully inserted, releasing the upper point 46 from engagement with the recess in the lever.

In order to overcome the variation in weight of similar and also various materials, we provide adjustable positive stop means for controlling the distance of the movement of the lever handle to thereby govern the amount of material passing from the spout into the plural compartment scoop. This stop means comprises the slidable and centrally slotted members 47 one of which is shown in Fig. 11 and which are in positive clamped down engagement on each side of the lever clearance path 28 by hexagon-headed screws 48; the process of adjustment being to move the right and left slide pieces either toward or from the adjacent side of the lever 25 a proper distance for right or left movement of the lever to allow a proper quantity of material which is to be drawn from the spout to flow into either of the scoop compartments; the area of the spout opening uncovered by the valve 24 being determinable by the position of the members 47 which are then tightened securely to the upper face of the base wall 49 by means of the hexagon-headed screws.

The size of the vertical stream flow of material from the spout into the scoop, has a bearing on the manner in which the material builds up in each compartment of the scoop during the charging or accumulation period of the required weight.

As certain kinds of roasting coffee are heavier and less bulky than other kinds, it follows, that the adjustment feature will vary the size of flow opening and thereby the amount of deposit in the scoop, and is of practical value.

The upper rim or collar portion 50 of the base 13 is secured thereto by means of the spout ears 51 and the overlapping edge 52 of the spout which edge fits over the upper edge 53 of the inner wall portion 54 of the collar 50, the ears 51 having holes 55, through which screw means 56 which may be either the rod, shown in Fig. 7, or the regulating screw, indicated in Fig. 5, project downwardly into threaded bores 57 of lugs 58 at

the upper end of base 13, thereby holding the spout fast to the base, and also the collar 50.

The collar 50 has formed therein an annular recess, which recess functions to receive and to firmly hold the lower end 61 of an open-ended glass cylinder 62. This glass member, which may be of any suitable shape or outline, may also be made fast to the base assembly by means of rods 56 which pass upward therethrough and which are secured to the inner flange rim 63 of the top ring frame 65; the upper threaded end of each rod 56 passing through an alined perforation in the flange 63, where the nut 64 functions to tie the rod and top ring together and to bring downward pressure to bear on the upper end 68 of the glass member 62, see Fig. 8.

The ring 65 has formed thereon the overlapping flange or projection 69 which fits into a recess 70 formed at one side of the edge wall of the capped top lid 71. This projecting flange acts as a catch which in cooperation with the lock staple 72 fastened to the ring 65 and the slotted portion 73 of the top lid 71 serves to securely fasten the lid to the ring when a padlock (not shown) is attached to the lock staple at perforation 73 therein.

In order to form a seal-tight compartment of the containing space in the glass cylinder, plastic material 75 is placed between the upper edge of the cylinder and the ring 65, and also between the lowered edge of the lid and the flange rim 63. To further insure this feature, a similar packing 76 may also be placed between the overlapping spout rim 52, and upper edge 53 of the inner wall of the collar 50.

The showing in Fig. 12 relates to a different form of agitating means, the spout 19 having mounted therein at 77 the oscillating member 78 which is caused to swing to the right or left when the valve plate is moved, the slotted portion 80 engaging the lower end of the agitating member. This form will be found useful in positively driving the material in the spout toward that side thereof which is open when the valve plate 24 is moved, thus causing considerable agitation and breaking up any vacant space present between the particles of the material which is to be ground from the spout.

When a cabinet such as herein shown is tightly sealed at all points and the material such as finely ground or whole bean coffees are drawn therefrom, vacant spaces are produced which tend to reduce the action of gravity on the material. This is one reason why the spout is shaped as shown in the various figures; particularly it is important that the lower end be shaped as shown, as by this particular shaping the material at the extreme lower end of the spout will be

free from any impeding support from the walls of the spout and thus free to fall or drop into the scoop, which lies directly below. The agitating means insures that this early start of the material is instantly or simultaneously followed up by a flow movement from the upper portion of the spout to replace the falling particles and in this way an instantaneous stream flow of the material into the scoop is secured without the need on the part of the operator to otherwise manually assist the discharge from the spout.

We claim:

15. 1. In a merchandising counter case the combination of a display section and a hollow base having an opening, a scoop having at one end means to close said opening and also having separated measuring elements 20 for obtaining separate quantities from the material held in the display section and a valve in the base above the scoop and movable in one direction to allow material to flow into one element and in the opposite 25 direction to allow the material to flow into another element of the scoop.

2. In a display case for servicing freshly roasted coffee and like materials to the retail trade a combination of a display element, of 30 a base element, and a top cover element, with means for sealing the respective elements together to preclude air movements through the display element, and other means associated with the base element for partly insulating the same against temperature changes, said means forming closed air 35 chambers in the side portions of the base element.

3. The combination with a base of a display cabinet and vending machine, of a flow-spout, a cut-off valve and agitating means mounted on said valve for stirring the material in the flow-spout at the time of movement of the valve, a measuring device below 45 the valve having a plurality of compartments the valve being movable in one direction to fill one compartment and in another direction to fill another compartment while the measuring device remains stationary.

4. A display cabinet having a base section and a spout inside the base section, a cut off valve for the spout, adjustable means to limit the movement of the cut off valve, a measuring device below the cut off valve cooperative 55 with said adjustable means to accurately determine the amount of material that may pile up in the measuring device, said measuring device being movable into and out of the base section independently of the cut off 60 valve.

5. A display cabinet having a base section and a spout inside the base section, a cut off valve for the spout having a handle extending outside the base section whereby the cut off valve may be moved, adjustable means

on either side of the handle to limit the movement thereof and the cut off valve, a measuring device having a plurality of compartments below the cut off valve, the cut off valve being movable in different directions to allow the material to flow through the spout into different compartments. 70

6. A display cabinet having a base portion, a spout therein, a cut off valve for the spout, a measuring device in the base portion beneath the cut off valve said measuring device having a plurality of compartments and adjustable means to regulate the amount of movement of the cut off valve to measure the amount of material passing through the spout into the different compartments of the measuring device. 75

7. In a cabinet for vending granular materials the combination of a casing, a two compartment scoop having a single outlet 80 mouth through which material may pass from both compartments said scoop being movable into and out of the casing and means in the casing movable independently of the scoop to allow the material to flow into either compartment of the scoop. 85

8. A display cabinet comprising a transparent display section, a base section and a top cover for the display section, air excluding packing between said sections and a measuring device movable into and out of the base section said base section having an opening therein and means on the measuring device to close said opening when said measuring means is located in the base the base section having partition walls on either side of said measuring means to form dead air chambers in said base section. 95

9. A display cabinet having a base section, a spout therein and a cut off valve below the spout pivoted in the base section for movement from left to right, a measuring device movable into and out of the base section and having a partition extending from front to rear of the base section below said cut off valve said partition dividing the measuring device into two compartments one of which may be filled when the cut off valve is moved to the left and the other of which may be filled when the cut off valve is moved to the right. 105

10. In a dispensing device for measuring coffees and like materials from a cabinet, a cut off valve for the cabinet arranged beneath the same, a plural compartment scoop below the cut off valve, said valve being movable to allow materials to flow from said cabinet to either compartment of the scoop while preventing the flow simultaneously to more than one compartment. 110

11. In a display cabinet, the combination of a hollow base having an opening therein, a transparent display section above the base, means within the base for measuring off half pound and pound quantities from the mate. 125

rial held in the display section, said means including a spout, a movable cut off valve at the lower end of the spout and a plural compartment scoop movable into and out of the opening in said base.

5 In testimony whereof we have hereunto affixed our names and signatures this twenty-second day of May, 1928.
